CLAIM

The ornamental design for a motorcycle mirror, as shown and described.

DESCRIPTION

FIG. 1 is a front elevational view of a motorcycle mirror showing our new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a front perspective view thereof;

FIG. 8 is a rear perspective view thereof; and,

FIG. 9 is a reference view of the motorcycle mirror, shown in position of use.

In the drawings, the broken lines in FIG. 9 showing a motorcycle form no part of the claimed design.
